UNITED STATES PATENT OFFICE.

FREDERICK C. GILBERT, OF HARTFORD, CONNECTICUT, ASSIGNOR TO POPE MANUFACTURING COMPANY, OF HARTFORD, CONNECTICUT, A CORPORATION OF NEW JERSEY.

DESIGN FOR A BICYCLE-FRAME.

No. 39,620.

Specification for Design.

Patented Oct. 13, 1908.

Application filed February 25, 1907. Serial No. 359,309. Term of patent 7 years.

To all whom it may concern:

Be it known that I, FREDERICK C. GILBERT, a citizen of the United States, residing at Hartford, in the county of Hartford and State of Connecticut, have invented a new, original, and ornamental Design for Bicycle-Frames, of which the following is a specification, reference being had to the accompanying drawing, forming a part hereof.

The figure is a view in side elevation of a bicycle frame showing my invention.

I claim:

The ornamental design for a bicycle frame as shown.

FREDERICK C. GILBERT.
